CLAIM

The ornamental design for a vial adaptor, as shown and described.

DESCRIPTION

FIG. 1 is a top, front, right side perspective view of a vial adaptor embodying our new design;

FIG. 2 is a bottom, front, right side perspective view of the vial adaptor of FIG. 1;

FIG. 3 is a front view of the vial adaptor of FIG. 1, the back being a mirror image thereof;

FIG. 4 is a right side view of the vial adaptor of FIG. 1, the left side being a mirror image thereof;

FIG. 5 is a top plan view of the vial adaptor of FIG. 1;

FIG. 6 is a bottom plan view of the vial adaptor of FIG. 1;

FIG. 7 is a front view of the vial adaptor of FIG. 1 coupled to a vial;

FIG. 8 is a top, front, right side perspective view of a piston portion of a vial adaptor of FIG. 1;

FIG. 9 is a bottom, front, right side perspective view of the piston portion of a vial adaptor of FIG. 8;

FIG. 10 is a front view of the piston portion of a vial adaptor of FIG. 8, the back being a mirror image thereof;

FIG. 11 is a right side view of the piston portion of a vial adaptor of FIG. 8, the left side being a mirror image thereof;

FIG. 12 is a top plan view of the piston portion of a vial adaptor of FIG. 8;

FIG. 13 is a bottom plan view of the piston portion of a vial adaptor of FIG. 8;

FIG. 14 is a front view of the piston portion of a vial adaptor of FIG. 8 coupled to a vial;

FIG. 15 is a top, front, right side perspective view of a cap portion of a vial adaptor of FIG. 1;

FIG. 16 is a bottom, front, right side perspective view of the cap portion of a vial adaptor of FIG. 15;

FIG. 17 is a front view of the cap portion of a vial adaptor of FIG. 15, the back being a mirror image thereof;

(Continued)

FIG. 18 is a right side view of the cap portion of a vial adaptor of FIG. 15, the left side being a mirror image thereof;

FIG. 19 is a top plan view of the cap portion of a vial adaptor of FIG. 15;

FIG. 20 is a bottom plan view of the cap portion of a vial adaptor of FIG. 15; and,

FIG. 21 is a front view of the cap portion of a vial adaptor of FIG. 15 coupled to a vial.

The broken lines in the drawings illustrate portions of the vial adaptor and its environment which forms no part of the claimed design.
